UNITED STATES PATENT OFFICE.

JOHN L. CLARKSON, OF GILLESPIE, ILLINOIS.

AUTOMATIC CAGE-SAFETY.

1,150,341.

Specification of Letters Patent. Patented Aug. 17, 1915.

Application filed July 28, 1914. Serial No. 853,684.

To all whom it may concern:

Be it known that I, JOHN L. CLARKSON, citizen of the United States, residing at Gillespie, in the county of Macoupin and State of Illinois, have invented certain new and useful Improvements in Automatic Cage-Safety, of which the following is a specification.

My invention relates to new and useful improvements in safety automatic car stops such as are employed generally in mining equipment, and are particularly used in connection with the lift cages by means of which the pit cars are carried from the working level to the surface.

The principal object of my invention is to provide novel actuating mechanism for automatically controlling the movement of the stops into operative or inoperative position.

A further object is to provide a controlling mechanism for the horn stops which is normally held by yieldable means in operative position for preventing movement of a pit car on the cage carried section of the track until the cage has been lowered or raised to the desired predetermined position.

A still further object is to so construct the horn stop controlling mechanism that the stops will be automatically moved into inoperative position to permit the passage of a pit car from the cage when the cage has been lowered to the bottom of the shaft, and will automatically return the stops to operative position simultaneously with the movement of a loaded pit car onto the cage platform.

The above and additional objects are accomplished by such means as are illustrated in the accompanying drawings, described in the following specification, and then more particularly pointed out in the claims, which are appended hereto and form a part of this application.

With reference to the drawings, wherein there has been illustrated the preferred embodiment of this invention as it is reduced to practice, and throughout the several views of which similar reference numerals designate corresponding parts, Figure 1 is an end elevation of a lift cage, showing the automatically operated stops in operative position. In this view there appears in the lower portion a solid line illustration of the cage in position at the bottom of a shaft and with the stop members disposed in in-

operative position, while in the upper portion of the figure is disclosed a dotted line illustration of the cage lifted from the sump blocks of the mine shaft and showing the stop members in operative position; Fig. 2 is a section on the line 2—2 of Fig. 1; Fig. 3 is a composite view showing the actuating mechanism employed in automatically controlling the movement of the stop members, the various elements of the mechanism being shown in disassembled relation but being arranged to indicate the manner in which they are adapted to be assembled when in use; Fig. 4 is a detail view taken longitudinally of the operating shaft by which the horn stops are actuated and showing in detail the construction of the clutch; Fig. 4^a is a section on the line 5—5 of Fig. 4. Fig. 5 is a view of a modified form of my invention in side elevation showing particularly a pair of additional stops which I may use in connection with the horn stops and disclosing also a manually operable clutch releasing mechanism. Fig. 6 is a detail perspective view of the clutch releasing mechanism. Fig. 7 is a detail perspective view of one of the stops shown in Fig. 5, showing in connection therewith a manually controlled lever and an automatic winding drum which are employed in moving the said stop into inoperative position.

In the drawings, I have illustrated the stop mechanism as applied to a lift cage 10 of the type employed in mines. The cage 10 is of the usual construction, and, since it does not form a part of this invention, has been illustrated conventionally. A pair of rails, indicated at 11 and 12 are, of course, laid on the floor of the cage to receive the cars which are being raised or lowered.

A pair of stop members, designated as entireties in the drawings by the numerals 13 and 14, are pivotally mounted on pins 15 which are carried by suitable brackets 16. The brackets are, of course, secured to the floor of the cage 10 in any desired manner, and are so positioned that the members 13 and 14 may be swung to a position over the rails 11 and 12 or may be swung outwardly, as shown in the lower portion of Fig. 1, to permit the free passage of the car wheels on the tracks as when an empty car is being displaced from the cage. The horn stops 13 and 14 are connected at their lower terminals to a pair of operating links 17 and 18 respectively by pivot pins 19.

The links 17 and 18 are at their inner terminals connected by pins 20 to a rock arm 21 which, as best shown in Fig. 3, is splined on the actuating shaft 22 whereby it may move longitudinally of the shaft but is constrained to oscillate therewith. Preferably, as shown in Fig. 3, the terminals of the rock arm 21 are equipped with spaced apertured ears 23 which pivotally receive the reduced terminals 24 of the links 17 and 18.

From the foregoing description, it will be readily appreciated that the rotation of the shaft 22 in one direction will operate to swing the stop horns 13 and 14 into operative position over the rails 11 and 12, while the opposite rotation of the shaft 22 will swing the stop horns outwardly to permit the passage of the wheels of a car on the track, as shown in the lower portion of Fig. 1. The stop horns 13 and 14 are normally held in operative position over the rails 11 and 12 by means of a counterpoise or weight 25 which, as shown in Fig. 3 particularly, is carried by a rod 26, the upper terminal of which is secured to the shaft 22 by an attaching plate 27.

Inasmuch as the stop horns 13 and 14 are normally held in operative position over the rails by the weight 25, it is, of course, necessary to provide means for automatically swinging them into inoperative position when the cage reaches the bottom of the mine shaft so that the empty car being lowered may be quickly displaced from the cage to permit the operators to run a loaded car onto the cage. For this purpose a crank 30 has been provided. This crank is substantially L-shaped, having its lower terminal 40 bent to extend at right angles, as indicated at 31. On the upper terminal of the crank 30 is formed a sleeve 32 which is freely mounted on the forward terminal of the shaft 22, being held against complete withdrawal therefrom by means of nuts or similar fastening devices, indicated at 33. Inasmuch as the sleeve 32 of the crank 30 is freely mounted on the shaft 22, it is necessary to provide some means whereby the 50 sleeve may be held against rotation when the cage is being lowered to the sump block. For this purpose I have provided a clutch member 34 which is mounted slidably on the shaft 22 so as to rotate therewith in the manner best shown in Fig. 4^a. Clutch teeth, indicated at 35, are formed on one terminal of the clutch 34 and are engageable with clutch teeth 36 formed on the terminal of the crank sleeve 32.

60 Inasmuch as the clutch member 34 is bound to rotate with the shaft 22, it is obvious that when the clutch is in engagement with the sleeve 32 the crank 30 will be in effect fixed on the shaft. It, therefore, follows that when the cage is lowered into the

mine shaft the shaft 22 will be swung to draw the links 17 and 18 inwardly, moving the horn stops 13 and 14 into inoperative position as a result of the engagement of the member 31 with the sump block, indicated by the numeral 37. The upper terminal of the sump block is cut to produce the concave or cam edge 38. In order to normally hold the clutch 34 in engagement with the crank sleeve 32, so that the crank 75 will be normally fixed on the shaft 22, I have provided the clutch spring 39. This clutch spring bears against the rear terminal of the clutch 34, being held against movement on the shaft 22 by a stop collar 40, as 80 shown in Fig. 3.

As a means for accomplishing the automatic return of the stop members 13 and 14, I have provided a trip lever 41 which is pivoted to a suitable bracket 42 depending from the floor of the cage. This trip lever 41 is in the nature of a substantially V-shaped bell-crank lever, the one arm of which is bent to produce a lateral extension 43, which is adapted to be engaged by the 90 flange of the car wheel, as shown in Fig. 1. The arm 44 of the trip lever is provided with an offset apertured ear 45 to which is secured one end of a clutch chain 46. The other terminal of this chain 46 is, of course, 95 secured to the clutch member 34 by being attached to an eyelet or similar device 47.

It will be apparent that after the cage has been lowered into the mine shaft and the crank member 30 by engagement with the 100 sump block 37 has swung the horn stops 13 and 14 into open position, that the weight 25 has been swung upwardly to abnormal position, and that the weight will swing downwardly by gravity to extend the links 105 17 and 18 and, consequently, return the stops 13 and 14 to operative position as soon as the clutch 34 has been disengaged from the sleeve 32. Obviously then the oncoming loaded car will by the engagement of its 110 wheel flange with the lateral extension 43 of the trip lever swing this lever so that the chain 46 will be drawn forwardly with the resultant sliding of the clutch 34 on the shaft 22. The sliding of the clutch will disengage the teeth 35 thereof from the teeth 36 and from the crank sleeve 32, and as soon as the teeth are disengaged the member 25 will swing downwardly by gravity, thus 115 moving the rock arm 21 to normal horizontal position. In this manner the movement of the loaded car onto the cage automatically disengages the clutch 34 from the crank sleeve 32, permitting the weight 25 to 120 return the stop horns 13 and 14 to operative 125 position.

From the foregoing description it will be observed that as soon as the lift cage reaches the bottom of the shaft the crank member 30 will by engagement with the sump block 130

87 automatically swing the stop horns into inoperative position to permit the removal of the empty car from the lift cage. It will also be noted that the movement of a loaded car onto the cage will automatically effect the return of the stop horns to operative position over the rails so that the loaded car cannot be run through the cage.

In Fig. 5 I illustrate additional stops 10 which may be provided to hold the car in the event of breakage of either of the stops 13, 14. These additional stops consist of a pair of stop arms or bars 50 and 51 which are pivoted intermediate their lengths on 15 pins 52 to the longitudinally extended vertically disposed supporting plate 53 which is properly mounted on the platform of the lift cage. The lower terminals of these stop arms 50 and 51 project through slots formed 20 in the lift cage platform and are connected at their lower terminals to a pair of retractive helical springs 54 and 55. The lower terminals of these springs 54 and 55 are secured by an eyelet or similar fastening device 56 to one of the rollers 56' of the lift cage. Thus it will be seen, by referring to Fig. 5, that the upper terminals of the members 50 and 51 are normally held so that they may engage against the sides of a dog 30 57 which is secured to the bottom of the car indicated at 58, and extends transversely thereof. Assuming that the car is pushed onto the lift cage in the direction indicated by the arrow marked 59 in Fig. 5, it will be 35 obvious that the dog will first engage the free upper terminal of the member 50 depressing the same against the tension of the spring 54. Having passed over the free terminal of the member 50 the dog will engage 40 the upper terminal of the second stop arm 51 and will thus be held against further movement across the lift cage. Simultaneously with engagement of the dog 57 with the member 51 the spring 54 will act to return the upper terminal of the member 50 to its former position in which it engages against the dog. Obviously, therefore, the car having been pushed on the platform may 45 be held against displacement therefrom by the stop arms 50 and 51, even if the horn stops should be broken or for any other reason should fail to work. If desired, the stop arm 51 may be manually controlled as by a bell-crank lever 60 which is pivoted to a vertically disposed bracket 61 carried by the lift cage platform. It will be seen that by depressing the handle 62 of this lever the upper terminal of the stop arm 51 may be 50 swung downwardly into inoperative relation to the dog so that the car may be pushed from the lift cage when the latter is in dumping position at the sump block.

It will be apparent, however, that it is desirable to automatically disengage the member 51 from the dog so that under nor-

mal conditions when the lift cage is lowered to dumping position the stop arm 51 as well as the horn stops will be moved into inoperative position permitting the car to be pushed from the cage. For this purpose, 5 therefore, I have connected the upper terminal of the stop arm 51 to a winding drum 63 on the shaft 22 by means of a cable or chain 64. It will be apparent that when the lift cage is lowered to dumping position 10 and the crank 30 engages the sump block 15 the shaft 22 to which the drum 63 is attached will be rotated in the manner hereinbefore described, causing the cable 64 to be wound on the drum and resultantly withdrawing 20 the upper terminal of the stop arm 51 from engagement with the dog.

The above described automatic withdrawing of the stop arm 51 from engagement with the dog is desirable, of course, under all 25 normal conditions, but in case the cage is returned to dumping position after having been only partially lifted, it is undesirable that either the stop arm 51 or the horn stops be withdrawn from operative position. As 30 previously explained the horn stops and, as will now be apparent, the stop 51, may be maintained in operative position by releasing the clutch 34 at the moment the crank 35 30 engages the sump block. For this purpose, therefore, I have provided at the loading platform a clutch releasing device shown 40 particularly in Fig. 6. This device includes a hand lever 65 which is pivoted at its lower terminal as in Fig. 5 to a convenient portion 45 of the loading or sump platform 66 and is freely connected intermediate its length by a link 67 to an L-shaped arm 68. This arm 68 may be slidably mounted in suitable 50 guides which can be attached to the loading platform. From the platform of the lift cage there depends a bracket 69 to the lower 55 terminal of which is pivotally connected, as by a pin 70, the lower terminal of an arm 71. Intermediate the length of this arm 71 there 60 is rigidly secured a horizontally disposed arm 72 which is of such length that it will be engaged by the vertical portion 73 of the member 68 when the lever 65 has been swung to project this member 68 into the pit. A 65 chain indicated at 74 is employed in connecting the arm 71 to the clutch 34. It will thus be seen that if the tipple man signals the engineer to return the cage bearing a 70 loaded car to the loading platform, he (the 75 sump man) may cause the clutch 34 to be released immediately upon the engagement of the cranks 30 with the sump block, thus bringing the weight 25 into action so that the horn stops 13 and 14 and member 51 will 80 be immediately returned to operative position.

The stop members 50 and 51 and the controlling mechanism therefor may be eliminated, but I prefer to employ them as the 85

liability of accidental movement of the car from the cage is thereby minimized.

In reduction to practice, it has been found that the form of this invention illustrated 5 in the drawings, and referred to in the above description as the preferred embodiment, is the most efficient and practical; yet, realizing that the conditions concurrent with the adoption of this device will necessarily vary, 10 it is desirable to emphasize the fact that various minor changes in details of construction, proportion and arrangement of parts may be resorted to, when required, without sacrificing any of the advantages of the invention, as defined in the appended claims. 15

Having thus described the invention, what is claimed as new is:—

1. In a safety apparatus, the combination with a lift cage having a track section, and 20 a landing having a sump block, of a stop member on the cage, means for normally holding the stop in closed position over the track, means on the cage engageable with the sump block for automatically moving the 25 stop member into open position when the cage engages the landing whereby an empty car lowered in the cage may be displaced therefrom, and means on the cage actuated by a car moving onto the cage track for 30 effecting return of the stop member to closed position.

2. In a safety apparatus, the combination with a lift cage having a track section, and a landing having a sump block, of a stop 35 member, means for normally holding the stop in closed position over the track, means engageable with the sump block for automatically overcoming the first-mentioned means to move the stop to open position 40 simultaneously upon the engagement of the cage with the landing, and means operable by a car moved onto the cage track for releasing the second-mentioned means whereby the first-mentioned means may again act 45 to return the stop to normal closed position over the track.

3. In a safety apparatus, the combination with a lift cage having a track section, and a landing having a sump block, of a stop 50 member, a rock arm connected with the stop member, a shaft keyed to the rock arm, means carried by the shaft and engageable with the sump block for rotating the shaft and swinging the stop into open position 55 upon the engagement of the cage with the landing, and means carried by the cage and engageable by a car which is being moved onto the cage for effecting the return of the stop to closed position.

60 4. In a safety apparatus, the combination

with a lift cage having a track section, and a landing having a sump block, of a stop, means normally holding the stop in closed position over the track, said means including a rock arm connected with the stop, a 65 shaft on which the rock arm is keyed, a weight connected to the shaft for normally holding the rock arm in horizontal position, a crank freely mounted on the shaft, a clutch on the shaft, yieldable means holding the 70 clutch in engagement with the crank whereby the crank is normally locked to the shaft, said crank being engageable with the sump block when the cage engages the landing for rotating the shaft with a resultant swinging 75 of the rock arm and movement of the stop to open position, and a trip member normally extending above the track section and engageable by the wheel of an on-coming 80 car for releasing the clutch from engagement with the crank, whereby the weight may swing downwardly to return the stop to normal closed position over the track.

5. The combination of a lift cage, a landing having a sump block, a rock shaft 85 mounted on the cage, a stop member mounted on the cage, connections between the stop member and the rock shaft, means acting upon the rock shaft to normally hold the stop member in closed position, a crank arm 90 adapted to engage the sump block, means for locking said crank arm to the rock shaft whereby the engagement of the crank arm with the sump block will move the stop member to open position, and means for releasing the crank arm from the rock shaft 95 whereby the stop member may return to closed position.

6. The combination with a lift cage having a track section, and a landing having a 100 sump block, of a rock shaft mounted on the cage, a stop member mounted on the cage and connected with said rock shaft, a clutch member on said rock shaft, an operating arm loosely mounted on the shaft and 105 adapted to engage the sump block and be locked to the rock shaft by the clutch member whereby to swing the stop into open position at the side of the track section, means for releasing the clutch member from 110 the operating arm, and means acting on the rock shaft to move the stop member to closed position over the track section when the clutch member is released.

In testimony whereof I affix my signature 115 in presence of two witnesses.
